US00D499083S

(12) **United States Design Patent** (10) Patent No.: **US D499,083 S**
(45) Date of Patent: **** Nov. 30, 2004**

(54) **COMBINED DISC PLAYER, RADIO RECEIVER AND TAPE RECORDER**

(75) Inventor: **Soichi Tanaka**, Tokyo (JP)

(73) Assignee: **Sony Corporation**, Tokyo (JP)

(**) Term: **14 Years**

(21) Appl. No.: **29/194,941**

(22) Filed: **Dec. 4, 2003**

(51) LOC (7) Cl. **14-01**

(52) U.S. Cl. **D14/168**

(58) Field of Search **D14/135-136, D14/156-157, 160-165, 167-168, 193-198, 188-189, 496; 455/347-351; 369/75.1, 75.2, 77.1, 77.2**

(57) **CLAIM**

The ornamental design for a combined disc player, radio receiver and tape recorder, as shown.

DESCRIPTION

FIG. 1 is a perspective view of a combined disc player, radio receiver and tape recorder showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
